UNITED STATES PATENT OFFICE.

GUSTAVE WENZELMANN, OF GALESBURG, ILLINOIS.

ELECTRIC STOVE OR IRON.

1,093,510.

Specification of Letters Patent. **Patented Apr. 14, 1914.**

Application filed November 11, 1913. Serial No. 800,314.

To all whom it may concern:

Be it known that I, GUSTAVE WENZELMANN, a citizen of the United States, and a resident of Galesburg, in the county of Knox and State of Illinois, have invented a new and useful Electric Stove or Iron, of which the following is a specification.

My present invention relates primarily to the heating element for electrically heated stoves, sad-irons, grids and similar devices, and the principal object thereof is to generally improve the construction and to increase the utility and efficiency of devices of like or similar nature.

15 A subsidiary object is to provide a device of the character noted which will become hot in a very short time, whereby economy in electric current is subserved.

20 Another object is to provide means connected with or attached to the heating element whereby simplicity and economy of construction are attained.

25 Minor objects will be in part obvious and in part specifically pointed out.

30 In the accompanying drawings, illustrating preferred embodiments of my invention, Figure 1 is a top plan of a stove in which my improvements are incorporated; Fig. 2, a longitudinal central sectional view thereof; Fig. 3, a bottom-plan of the base and attached parts, somewhat reduced with relation to Figs. 1 and 2; Fig. 4, a side elevation of the same, similarly reduced; Fig. 5, a modification, a top plan of a sad-iron, reduced with reference to Fig. 6; and Fig. 6, a longitudinal section taken in the plane of the line 6—6 in Fig. 5, but enlarged with reference thereto and showing additional features.

40 Coming now to a detailed description of said drawings, and referring to each element and part thereof, where necessary, by a distinguishing reference numeral, uniformly employed, 2 designates a heating element, which in the stove is contained in the top and in the iron contained in the bottom.

Reference is now to be had particularly to Figs. 1-4 inclusive. 3 designates the top or plate provided with an annular flange 4 cut away at 7, and with an annular boss 5. 6, 6 indicate bosses projecting from the under side of the plate and each provided with a centrally arranged threaded recess. 8, 8 indicate grooves in the face of the plate, and 9

designates a projection extending inwardly 55 from the boss 5.

The stove bottom is a casting comprising a disk 10 the rim of which seats within the flange 4 and rests against the boss 5. It is provided on one edge with a pocket 11 which is adapted to sustain the weight of an attachment plug 12, the clip 13 of which engages the lower wall thereof. In its edge the disk is provided with notches 14 which permit of the passage of assembling screws 15 which first pass through the upper ends of supporting legs 16 and the terminals of which engage threaded recesses in the boss 5 of the upper casting. On its lower face the stove bottom is provided with a box-like projection 17 having in its side walls threaded recesses for the reception of assembling screws 18 by which an L-shaped closure 19 (which completes the box) is secured thereto. The disk bottom is cut away to provide 75 an opening 20.

21 indicates an asbestos or other heat-resisting ring running around the inner face of the annular boss 5.

22 indicates one and 23 the other terminal 80 of a resistance coil 24. This coil is formed preferably of a thin, narrow convolute ribbon of any suitable metal.

26 is an insulating bushing, its smaller end seated in an aperture in the L-shaped closure 85 19 and its inner end resting against an L-shaped bracket 27 having an inverted cup-shaped upper portion 30 provided with an eye through which a screw 28 is passed, its threads engaging a boss 6. 29 indicates a 90 mica washer seated in the cup 30, and 31 indicates a similar washer seated on top of said cup, through which washers said screw 28 passes and by which it is insulated from said cup. 95

32 designates a terminal post, its inner end engaged with a bracket 27 and its stem resting in a bushing 26.

The elements 26, 27, 28, 29, 31 and 32 are duplicated in elements correspondingly numbered. Screws 33 are threaded into suitable apertures in the bracket and provide means for connecting the resistance ribbon terminals thereto and thereby to the terminal posts 32. The body portion of the 100 ribbon or wire 24 is embedded in cement 34 possessing heat-conducting and electric-insulating properties, as are also a plurality

of asbestos cords 35 which are laid between proximal portions of said ribbon.

Considering the iron, 40 designates a casting having an aperture for the reception of 5 a screw 41 which engages threads of a boss 42 in the iron-body or plate 43, which latter is hollowed out to receive and hold a heating element similar to that hereinabove described.

10 44 designates a top or cap and 45 a handle. 46, 46 designate assembling screws, and 47, 47, fiber washers.

In the foregoing specification I have described two modes which may be adopted in 15 carrying my invention into effect, but have by no means endeavored to recite all which might be employed, the object of this specification and the drawings herein referred to being to instruct persons skilled in the art 20 to carry out the invention in the manner and form at present preferred by me; and I desire it distinctly understood that specific showing and mention by me of a modification is in no wise intended to exclude others 25 not referred to but which are within the spirit and scope of the invention as defined in the appended claims.

Having thus described the nature of my invention, I claim as new:

30 1. A device of the character described comprising a hollow body-member to be heated, said body provided with an annular flange, a heating element contained in said hollow body, a disk-like body-member insulated from the hollow-body member and provided with a box-like projection, a closure for said projection, terminal brackets within said projection, means for connecting them with the heating element, insulated 35 bushings supported by said closure, and ter- 40

50 minal posts insulated by said bushings from said closure and electrically connected with said brackets.

2. An electric stove comprising a hollow top-plate provided with an annular flange, 45 a heating element contained in said hollow body, a lower body-member provided with a box-like projection, a closure for said projection, terminal-brackets within said projection, a heating element intermediate said 50 body members, means for connecting it with said brackets, terminal posts insulated from said closure and electrically connected with said brackets, means for insulating said lower body-member from said heating element, legs having each a groove in which the annular flange of the top rests, and means 55 for securing said body members and legs together.

3. A device of the character described comprising a hollow body to be heated, said body provided with an annular flange, a heat-conducting, electric-insulating material contained in said hollow body, a resistance element enveloped by said material, an asbestos 60 cord also enveloped thereby and disposed intermediate adjacent portions of said ribbon but out of contact therewith, a pair of bosses 65 embedded in said material, a bracket supported by said bosses and insulated therefrom, and terminal posts engaged with said bracket.

In witness whereof I hereunto affix my signature at Galesburg, Ill., this 6th day of November, 1913, in presence of two subscr- 75 ing witnesses.

GUSTAVE WENZELMANN.
